UNITED STATES PATENT OFFICE.

OLAF S. BURMAN, OF MINNEAPOLIS, MINNESOTA.

BOILER-STAND.

1,346,875.

Specification of Letters Patent.

Patented July 20, 1920.

Application filed February 18, 1920. Serial No. 359,592.

To all whom it may concern:

Be it known that I, OLAF S. BURMAN, a citizen of the United States, residing at Minneapolis, in the county of Hennepin and 5 State of Minnesota, have invented certain new and useful Improvements in Boiler-Stands; and I do hereby declare the following to be a full, clear, and exact description of the invention, such as will enable others 10 skilled in the art to which it appertains to make and use the same.

My invention has for its object to provide an extremely simple and highly efficient stand for water boilers of the type commonly called range boilers, and to this end, 15 it consists of the novel devices and combinations of devices hereinafter described and defined in the claims.

In the accompanying drawings, which illustrate the invention, like characters indicate like parts throughout the several views.

Referring to the drawings:—

Figures 1 and 2 are fragmentary views, principally in elevation, showing a range 20 boiler supported on the improved stand with some parts sectioned; and

Fig. 3 is a detail view partly in plan and partly in horizontal section taken on the line 3—3 of Fig. 1.

The improved stand 4, as shown, is in the form of a single casting having a flanged 25 supporting base 5, and a saucer-like flanged upper end or top 6, on which is supported a range boiler 7. Formed in the body of the stand 4, near the top thereof, is a transverse opening 8 and a vertical cylindrical passageway 9, which extends centrally upward through the body of the stand 4 from the transverse opening 8 through the bottom of 30 the saucer-like flange 6.

A horizontal cold-water pipe 10 has on its delivery end an elbow coupling 11, which extends into the opening 8, and it will be noted that said opening is of such size as 35 to hold said elbow against horizontal swinging movement, but with freedom for a slight vertical movement. A nipple 12 completes the connection between the water supply 10 and the boiler 7. One end of this nipple 12 is screwed into a boss 13 on the bottom of the boiler 7 and its other end is screwed into the elbow connection 11.

In mounting the boiler 7 on the stand 4 and connecting the water supply 10 thereto, 40 the elbow connection 11 is inserted into the opening 8 and one end of the nipple 12 is screwed into the boss 13 and boiler 7. The

boiler 7 is placed over the stand 4 and the nipple 12 inserted into the passageway 9 by lowering said boiler until the lower end 45 of the nipple 12 enters the upper end of the elbow 11. The boiler 7 is then turned to rotate the nipple 12 and screw the same into the elbow connection 11 and thereby draw the boiler 7 onto the saucer-like flange 6 50 and the elbow connection 11 against the upper wall of the transverse opening 8, to securely hold the boiler 7 on the stand 4 and against tipping movement in respect thereto. The purpose of making the flange 6 in the 55 form of a saucer is to afford a definite supporting flange on the stand 4 for the boiler 7 and also to afford clearance or a pocket for the boss 13.

The above described boiler stand, while 60 extremely simple and of small cost to manufacture, is thought to be highly efficient for the purpose had in view. Obviously, the construction of the stand is such as to make it easy to sweep around and keep clean.

What I claim is:

1. The combination with a boiler, of a stand for supporting the boiler and provided with a transverse opening and a vertical passageway leading from said opening 65 through the top of the stand, a pipe coupling extending into said opening, and a nipple connection secured to the boiler extending through said vertical passageway and having screw-threaded engagement with the 70 pipe coupling.

2. The combination with a boiler, of a stand having a flanged base and a saucer-like top flange on which the boiler rests, 75 said stand being provided with a transverse opening and a vertical passageway leading from said opening through said top flange, a pipe coupling extending into said opening and held against horizontal movement, a boss on the boiler extending into the saucer-like top flange of the stand, and a nipple connection secured in said boss and arranged to be screwed into the pipe coupling by turning the boiler in respect to the stand to draw said pipe coupling against the wall 80 of said transverse opening to hold the nipple connection against endwise movement and the boiler on the stand.

In testimony whereof I affix my signature in presence of two witnesses.

OLAF S. BURMAN.

Witnesses:

WINIFRED I. WARD,
HARRY D. KILGORE.
